UNITED STATES PATENT OFFICE.

WINCENTY WORONIECKI, OF DICKSON, PENNSYLVANIA, ASSIGNOR OF ONE-HALF TO
JUSEF P. PANICZKOWSKI, OF THROOP, PENNSYLVANIA.

MEANS FOR PROTECTING THIRD RAILS.

1,410,440.

Specification of Letters Patent. Patented Mar. 21, 1922.

Application filed December 12, 1921. Serial No. 521,761.

To all whom it may concern:

Be it known that I, WINCENTY WORONIECKI, a citizen of Poland, residing at Dickson, in the county of Lackawanna 5 and State of Pennsylvania, have invented certain new and useful Improvements in Means for Protecting Third Rails, of which the following is a specification.

This invention relates to electric railways 10 and particularly to means for covering or protecting the third rail, whereby accumulations of sleet and snow on said rail are prevented and accidental contact of workmen or others with such rail is made impossible.

The object of the invention is to provide a movable shield or cover for protecting third rails and to devise positive car actuated means whereby such cover will be shifted so as to expose the rail as a car approaches, and will be restored to protecting position after the car has passed.

Specifically I propose to provide a shield or cover formed of a series of independently 20 movable sections arranged end to end, and to arrange car actuated mechanism whereby each section is shifted to expose the rail just before the car reaches such section, and each such shifted section is automatically restored to normal position after the car has 30 passed it.

In order that the invention may be clearly understood, reference is had to the accompanying drawings, illustrating one embodiment thereof, and forming part of this specification, in which drawings—

Fig. 1 is a plan view of a fragment of a track equipped with my invention, such view showing one traction rail and the third rail 40 with my improved shield applied thereto. A car is indicated in dotted lines, and the adjacent shield section is shown in its shifted position.

Figs. 2 and 3 are side elevations of the 45 track shown in Fig. 1, a car being illustrated as approaching from the right in Fig. 2 and as leaving at the left in Fig. 3.

Figs. 4, 5 and 6 are transverse sections on an enlarged scale illustrating in detail my 50 improved shield shifting mechanism, and showing the same in different positions. In these views parts are shown in elevation.

Figs. 7 and 7^a are a fragmentary plan and side elevation respectively, illustrating the 55 manner in which the actuating bars may be

adjustably secured to the car so as to be capable of occupying two different positions.

Referring to the drawings in detail, the usual track rail is indicated at 1 and is supported on ties 2. The third rail is shown at 3, and is illustrated as being supported in an elevated position by means of suitable carriers or chairs 4, the third rail itself being of course suitably insulated as indicated in Figs. 4, 5 and 6.

My improved shield or guard is indicated at 7 and, as shown, comprises an angular or trough shaped member which, when in normal position, overlies the third rail as illustrated in Fig. 4 in such a manner as to 70 form a cover or roof with sloping sides. This arrangement renders the cover particularly efficient in protecting the rail from the elements.

The shield or cover comprises a series of 75 independently movable sections, three of such sections, *a*, *b* and *c*, being shown in the drawings. Each section is pivotally supported by means of hinges 6 to upstanding portions 5 of the chairs 4, and the upper 80 end of the portions 5 preferably has a flat top as shown in Fig. 4 so as to act as a support for the cover when it is shifted so as to expose the rail.

To the ends of each section of the shield 85 are secured arms 8 and 9, and from the outer ends of these arms extend chains 10 to actuating arms or levers which will now be described.

At each junction point of the shield sections is disposed a pair of ramps shown as in the nature of leaf springs 11 and 12, having a convex upper surface. One end of these springs is free, while the other end is rigidly secured as at 13, to a plate 13^a extending along the ties. These ramps 11 and 12 may be made of any suitable length and may be secured to the plate 13^a at any point necessary to produce the desired results.

Secured rigidly to each of the inner ramps 100 11 is a pair of horizontally projecting arms 14 and 15, such arms being preferably bowed downwardly as shown in Figs. 4, 5 and 6, so as to clear the ramp 12. The outer ends of the arms 14 and 15 are connected by means 105 of the chains 10 to the arms 8 and 9 respectively. It will be understood that the chains 10 are preferably of such length as, when taut, to hold the shield sections in the position indicated at *c* in Fig. 4, in which 110

position the shield is just out of contact with the rail. Other means for holding the shield spaced from the rail may be provided if desired, or in some cases where the shield is 5 constructed of dry wood, it may rest directly upon the rail.

Pivoted to the side of a chair 4 adjacent one end of each shield section, is a restoring device in the form of a bell-crank lever 16, 10 mounted at 17 on a pivot. One end 18 of this lever projects under the ramp 12 in position to be engaged thereby, while the other end 19 of the lever is so positioned as to lie just below the shield section when it 15 rests in its inoperative position upon the top of the portion 5 of the chair, as indicated at *b* in Fig. 4.

A represents a car or locomotive of any usual type having the current collecting shoe 20 A' (see Fig. 1) which engages the third rail. At each end of the car A is mounted a bar or arm B so shaped and positioned as to engage the ramps above described. The bar B at the front of the car is arranged to engage the ramp 11 and the bar B at the rear of the car is arranged to engage the ramp 12.

In order to provide for backing up, or moving the car slightly in the reverse direction, it is necessary to equip each end of the 30 car with an additional bar or arm B'. The two bars B and B' at each end of the car are preferably held in brackets C provided with pairs of T-slots *d* in which similarly shaped T-heads on the bars fit and slide. 35 Chains *f* or the like, may be provided, by means of which the bars B and B' may be raised and lowered into and out of operative position, and when lowered, they may be held down by means of pins *e* or by any 40 other suitable device.

The operation of the system will now be briefly described, assuming the bars B to be lowered into operative position. As a car approaches from the right as in Fig. 2, the 45 bar B will engage the ramp 11, and will depress it as indicated in dotted lines. This operates through the arm 14 to exert a pull through the chain 10 on the arm 8 attached to the adjacent shield section *b*, and thus 50 turns such section on its hinges and throws it into the open or in-operative position indicated in Figs. 1 and 5. The car then passes along the portion of the track adjacent the section *b* as shown in Fig. 1, and 55 when the car has entirely passed section *b*, the bar B at the rear of the car engages the ramp 12 at the left of Figs. 1, 2 and 3, thus depressing it. The downward movement of this ramp 12 causes it to engage the end 18 60 of the bell-crank lever 16 and swing such lever on its pivot, thus causing the end 19 thereof to kick up and push over or swing back section *b* of the shield into its normal position as shown in Fig. 3.

65 It will thus be seen that as the car travels

along, it successively shifts each section of the shield away from the third rail so as to expose the same, and then, after it has passed, restores each section to normal position. It will also be noted that this shifting and restoring operation is mechanical and positive in both directions, no spring being employed. Each shield section when shifted, remains in inoperative position until positively thrown back or restored by the car engaging ramp 12.

As shown, the ramp 12 is preferably arranged higher than the ramp 11 so as to allow the ramp 12 to more easily work clear of the arms 14 and 15.

When it is desired to run the car a short distance in the opposite direction or to back up over a portion of the track just passed, the bars B are raised and the bar B' at what was the rear of the car is lowered. It will be noted from an inspection of Fig. 1 that the bar B at the front of the car is nearer the track rail and the bar B at the rear of the car is nearer the third rail. The bars B' are therefore similarly staggered but 80 reversely arranged, so that the bar B' at what is the rear of the car in Fig. 1 would be nearer the track rail. Thus when this bar B' is lowered and locked in operative position, and the car is run backward, the bar B' engages the ramp 11, thus depressing the arm 15 and swinging the associated shield section into position to expose the third rail. Continued movement of the car in this reverse direction, however, will not result in 90 restoring the shield section to its original position. However, it will be seen that the shield is automatically shifted to inoperative position as the car approaches it from a reverse direction, and this is sufficient to 95 enable the car to successfully back up.

It will be noted that when the ramp 11 is depressed by the bar B' as just described, the arm 14 carried thereby is also actuated, but the shield section to which this arm is 100 attached being already in the in-operative position, no effect will be produced.

While I have shown a specific method of constructing the bars B and B', it will of course be understood that I do not limit myself to any such details of construction. Any other desired method of adjusting the bars may be used, or, if preferred, a single bar, 115 shiftable to two positions may be employed.

What I claim is:—

1. The combination with a third rail, and a movable shield therefor, said shield being supported on hinges so disposed that it may be swung to and retained by gravity in either a position to cover the rail or to expose the same, and car-actuated means for positively shifting said shield from either position to the other.

2. The combination with a third rail, and a movable shield normally in position to

cover the same, of mechanical means, positively actuated by the car as it travels along, for first shifting said shield so as to expose the rail, and subsequently restoring the 5 shield to its normal position, and a flexible connection between said car actuated means and said shield.

3. The combination with a third rail, and a movable shield normally in position to 10 cover the same, said shield being composed of independently movable sections arranged end to end, of means located along the track spaced from said shield sections and actuated by the car as it approaches each section 15 to shift such section so as to expose the rail, and independent means positively actuated by the car as it passes away from each section to restore the previously shifted section to normal position.

20 4. The combination with a third rail, and a shield therefor composed of a series of independently movable sections arranged end to end, said shield sections being normally in position to cover the rail, of a pair of 25 ramps located at the meeting ends of each adjacent pair of shield sections and operatively connected thereto, and means carried by the car for engaging one of said ramps to shift the next section ahead into position 30 to expose the rail, and means carried by the car for engaging another ramp to return said section to normal position.

5. The combination with a third rail, and a pivoted shield therefor capable of occupying either a position to cover the rail or a position to expose it, of a pair of car actuated elements located along the track, a flexible connection between one of said elements and said shield to swing it in one direction, and a lever between the other of said elements 40 and said shield to shift it in the opposite direction.

6. The combination with a third rail, of a movable shield therefor angular or trough-shaped in cross-section, means for normally supporting said shield above the rail with its corner or ridge uppermost, so as to serve as a water-shed, and means for shifting said shield away from the rail so as to expose the same.

50 7. The combination with a third rail, of an angular or trough shaped shield therefor, supports along the track to which said shield is hinged, by one of its edges, means for swinging said shield about its hinges 55 into a position in which it overlies the rail, means for supporting it in this position, and means for swinging said shield back into position where the rail is exposed, the hinges being so located that the shield is retained 60 by gravity in said last mentioned position.

In testimony whereof I affix my signature.

WINCENTY WORONIECKI.
